UNITED STATES PATENT OFFICE.

FRANCIS C. GREEN, OF NEW YORK, N. Y.

DESIGN FOR AN ELECTRIC-HEATER CASING.

No. 39,040.

Specification for Design.

Patented Jan. 28, 1908.

Application filed November 30, 1907. Serial No. 404,629. Term of patent 14 years.

To all whom it may concern:

Be it known that I, FRANCIS C. GREEN, a citizen of the United States, residing at New York, in the county of New York and State of New York, have invented a new, original, and ornamental Design for Electric-Heater Casings, of which the following is a specification, reference being had to the accompanying drawing, forming part thereof.

The accompanying drawing shows a front

elevation of an electric heater casing embodying my design.

I claim:

The ornamental design for an electric heater casing as shown.

FRANCIS C. GREEN.
